UNITED STATES PATENT OFFICE.

JOHN T. H. DEMPSTER, OF SCHENECTADY, NEW YORK, ASSIGNOR TO GENERAL ELECTRIC COMPANY, A CORPORATION OF NEW YORK.

MERCURY-LAMP-STARTING DEVICE.

1,057,041.

Specification of Letters Patent. Patented Mar. 25, 1913.

Application filed November 9, 1905, Serial No. 286,515. Renewed April 4, 1908. Serial No. 425,167.

To all whom it may concern:

Be it known that I, JOHN T. H. DEMPSTER, a citizen of the United States, residing at Schenectady, county of Schenectady, 5 State of New York, have invented certain new and useful Improvements in Mercury-Lamp-Starting Devices, of which the following is a specification.

This invention relates to an attachment 10 for mercury lamps or other vapor electric apparatus, by means of which such apparatus may be advantageously thrown in circuit and maintained in operative condition irrespective of the disturbing influence of 15 other translating devices in circuit.

My invention also embodies various features for the protection of vapor electric apparatus during starting as well as when operating under normal working conditions.

20 Although my invention is of general application it is of peculiar value when applied to vapor lamps operating on a series circuit.

The details of my invention will be better understood by reference to the drawing forming a part of this specification.

The drawing shows a well-known form 25 of mercury vapor lamp equipped with my improved form of cut-in device together with other elements embodied in my present invention.

The lamp shown in the drawing comprises an exhausted envelop 1 of glass, provided with a solid anode 2 of graphite and a 30 cathode 3 of mercury or other suitable vaporizable material in which floats a magnetizable plunger 4 provided at its top with a small cup-shaped depression 5 filled with mercury. A high resistance filament 6 is 35 connected permanently to anode 2 and dips in the mercury of cup 5, thus completing an electric circuit through the lamp when the lamp is in its initial or starting condition and before the mercury arc has been 40 established within the tube. A solenoid 7 surrounds the lower part of the lamp tube in such a way that when energized by current it will draw down the plunger 4, and by so doing electrically disconnect the mercury of cup 5 from the lower end of filament 6 and thereby generate an arc which serves 45 to start the main arc of the tube in a manner well understood to persons skilled in the art.

50 In shunt with the vapor tube is a film cut-

out 8 comprising two spring metal clips 9 and 10 separated by a layer of paper 11 or other suitable insulating material, so that if an excess of voltage is developed between the terminals of the lamp, this paper insulation breaks down and the spring clips permanently short-circuit the lamp. A solenoid 12 is included in the connection between the cut-out clip 9 and the cathode terminal of the lamp, and is provided with a movable armature 13, carrying an upwardly projecting arm 14 of conducting material to which is secured a contact block 15 for purposes hereinafter described. Two carbons 16 and 17 are so disposed that when an arc 55 is drawn therebetween the arc shunts the mercury lamp. This arrangement is effected by connecting the lower carbon 17 with the cut-out clip 9, and the upper carbon 16 with anode 2 of the lamp which in 60 turn is connected to clip 10 of the cut-out.

A double coil solenoid 18 is included directly in the line circuit to carbon 16, so that when current flows between the carbons, or through the lamp, or through the cut-out, 65 this solenoid is energized. A U-shaped armature 19 has its two legs disposed in inductive relation to the two coils of solenoid 18, so that when current passes through the solenoid the armature is lifted. A dash pot 70 75 of ordinary form has its plunger 21 connected to armature 19, and thus serves to limit the freedom of motion of this armature and gives an appreciable time interval between the establishment of magnetism in 80 the solenoid and the completed movement of armature 19. This armature carries at its lower end a conducting arm 25 provided with a contact 26 adapted under certain conditions to engage with contact 15 of armature 13. A flexible conductor 27 connects armature 25 with clip 9 of the film cut-out. Armature 19 also supports an electrically insulated arm 28 employed to lift carbon 16 85 from engagement with the lower carbon 100 when the apparatus is started. Engagement between the end of armature 28 and carbon 16 is effected by means of the clutch mechanism 29 pivoted at the point 30, so that when arm 28 moves upward the clutch 95 105 29 firmly grips carbon 16, but when the arm is in its lowest position as shown in the drawing this clutch mechanism strikes against a fixed stop 31 and releases its hold on carbon 16, permitting the latter to slip 110

through until it contacts with the top of carbon 17.

The main terminals for the lamp and its adjuncts are designated by the reference numerals 32 and 33, and for completeness of illustration I have shown conductor 33 as leading to other lamps 34 and 35 connected in series with the one previously described and equipped with similar cut-in devices.

10 The operation of applicant's device is as follows: Current entering the apparatus from the source by way of conductor 32 passes through solenoid 18 to carbon 16, and then to carbon 17 and out through conductor 15 33. Solenoid 18 immediately begins to lift its armature 19, thereby separating the carbons and establishing an arc in shunt with the vapor lamp, and consequently in shunt with film cut-out 9. As this arc gradually 20 increases in length the voltage impressed on the mercury lamp also increases but dash-pot 20 so limits the movement of armature 19 that this increase across the lamp is relatively slow, thus giving the lamp ample time 25 to draw down its magnetizable plunger 4 and start the generation of vapor before the voltage on the lamp reaches an abnormal value. When the lamp starts, the current passes through solenoid 12 and thus lifts 30 contact 15 out of the path of contact 26, but if the lamp fails to start these two contacts finally engage, and thus establish a circuit in shunt with the lamp so that a metallic circuit is established directly between solenoid 18 and conductor 33, thus permanently 35 cutting the lamp out of circuit.

The gradual increase in lamp voltage afforded by the shunting arc and its coöperating dash-pot is advantageous for several reasons which will be better understood by first 40 considering certain peculiar characteristics of vapor lamps and of series circuits including such lamps. The lamp shown in the drawing is provided with a high resistance 45 filament 6 initially connecting the two electrodes and serving as a conducting path through the lamp before the mercury arc is established. This filament is so designed that during normal operation it carries practically no current; as a consequence it gives the lamp an initial resistance much higher than its normal running resistance. With several of these lamps directly in series on a 50 circuit, the total initial resistance of the circuit is made much higher than the normal resistance, and in fact so much higher that difficulty has sometimes been experienced in making the generator "build up", particularly with generators of the Brush type. 55 By the use, however, of the shunting arcs above described, the circuit is given an initial resistance somewhat lower than its normal resistance, so that this difficulty is entirely overcome. The shunt arcs also serve 60 to protect the film cut-outs during the start- 65

ing of the lamp, for if such cut-outs are properly adjusted to break down at a voltage somewhat above normal running voltage for the lamp, as for instance to break down at 80 volts, they would, if not protected by the carbon arc, break down during the starting operation of the vapor lamp when the drop between lamp terminals might reach 150 or 200 volts, because of the high resistance of the filament.

70 The movable element 4 of the lamp possesses a certain amount of inertia and makes it desirable to give to dash-pot 20 an action so sluggish that plunger 4 can perform its functions before the carbon arc reaches an abnormal length. I prefer to regulate the time interval of this dash-pot by the fit of its plunger 21.

75 As previously stated each lamp of the series circuit is equipped with its own sustained arc, dash-pot and other adjuncts, and I contemplate such an adjustment among the dash-pots that the lamps will not all start at once, but preferably will start one after another. This is advantageous in preventing one lamp from disturbing the action of the other lamps of the series, and also in preventing violent disturbances which might be present in the series circuit if all the lamps started at the same instant and consequently dropped simultaneously from high resistance to low resistance. This successive operation of the lamps is effected by giving different time constants to the different dash-pots of the series as may readily 80 be done during manufacture by varying the fit of the dash-pot plungers within their enclosing cylinders.

85 What I claim as new and desire to secure by Letters Patent of the United States, is,—

1. The combination of a series circuit, a plurality of vapor electric devices connected to said circuit, and automatic means for preventing the simultaneous starting of said vapor electric devices when said circuit is energized.

100 2. The combination of a series circuit, a plurality of electric devices connected thereto, a shunt path for each of said vapor devices, means for increasing the resistance of said shunt paths, and retarding means for preventing simultaneous increase in the resistance of said shunt paths.

105 3. The combination of a series circuit, a plurality of vapor electric devices connected thereto, means for establishing an arc in shunt with each of said devices and for increasing the length of each of said arcs to increase the voltage on said vapor devices, and retarding means for preventing simultaneous increase in the length of said arcs.

110 4. The combination of a series circuit, a plurality of vapor electric devices connected thereto, means for establishing an arc in shunt with each of said devices and for in-

- creasing the length of said arcs, and a dash-pot associated with each of said arcs to prevent a sudden increase in length thereof, said dash-pots being adjusted with different 5 retarding powers to prevent simultaneous starting of said vapor electric devices.
5. The combination of a vapor electric device comprising an evacuated envelop and electrodes therein, of means for establishing a sustained arc in shunt with said vapor device and for automatically increasing the voltage drop across said arc to increase the voltage on said vapor device at starting.
10. The combination with a vapor device having an evacuated envelop, a plurality of electrodes and electromagnetic means for establishing an arc between said electrodes, of means for establishing an arc in shunt with said vapor device and for increasing the 15 length of said shunting arc to increase the voltage on said vapor device at starting, and retarding means for preventing a sudden increase in the length of said shunting arc.
6. The combination with a vapor device having an evacuated envelop, a plurality of electrodes and electromagnetic means for establishing an arc between said electrodes, of means for establishing an arc in shunt with said vapor device and for increasing the 20 voltage on said vapor device at starting, and retarding means for preventing a sudden increase in the length of said shunting arc.
7. The combination with a vapor device having a plurality of electrodes and starting means for establishing an arc between said electrodes, said starting means having an appreciable inertia, of means for establishing an arc in shunt with said vapor device 25 and for increasing the length of said last named arc to increase the voltage across said vapor device, and means for retarding said increase in voltage to give said starting means time for advantageous operation.
30. 8. The combination of a vapor electric device, a distribution circuit for supplying energy thereto, a film cut-out in shunt with said device, contacts initially shunting said film cut-out and protecting it from the disruptive action of said distribution circuit, and means for increasing the distance 35 between said contacts to increase the voltage on said vapor device at starting.
9. The combination with a vapor electric device, of means for establishing a sustained 40
- arc in shunt with said device and for automatically increasing the length of said arc to simultaneously increase the voltage on said device at starting.
10. The combination of a vapor lamp, a 50 conducting path in shunt with said lamp, and means for producing an arc in said shunt path and for gradually increasing the length of said arc to gradually increase the voltage on said vapor lamp. 55
11. The combination with a vapor lamp, of arcing contacts connected to the terminals of said lamp, and automatic means for gradually moving said contacts to produce a sustained arc and gradually increase the 60 voltage across the terminals of the lamp.
12. The combination of a plurality of mercury vapor lamps connected in series, and automatic means for starting said lamps in predetermined succession, each lamp being 65 started on a potential higher than its normal operating potential.
13. The combination of a plurality of mercury vapor lamps disposed in series, of means for shunting each of said lamps, and 70 automatic means for successively opening the shunt path for said lamps to start the lamps one after another in a predetermined order.
14. A system comprising vapor electric 75 devices disposed in series and automatic means for starting said devices successively in a predetermined order.
15. In a series lighting circuit containing mercury vapor arc lamps, means for supplying 80 a high voltage successively and automatically to each of the lamps in series to start the same.
- In witness whereof, I have hereunto set my hand this 8th day of November, 1905. 85
- JOHN T. H. DEMPSTER.
